W. N. VANATTA

ELECTRIC HEATER

Filed Dec. 29, 1924

Inventor:
Willis N. Vanatta,
by *Alvanda S. Zentz*,
His Attorney.

UNITED STATES PATENT OFFICE.

WILLIS N. VANATTA, OF ONTARIO, CALIFORNIA, ASSIGNOR TO EDISON ELECTRIC APPLIANCE COMPANY, INC., OF CHICAGO, ILLINOIS, A CORPORATION OF NEW YORK.

ELECTRIC HEATER.

Application filed December 29, 1924. Serial No. 758,501.

My invention relates to electric heaters and has for its object the provision of simple and reliable means for protecting electric heaters from overheating.

More specifically my invention relates to temperature cut-outs for electrically heated devices whereby the electric heating circuit is opened upon the occurrence of a predetermined maximum temperature. My invention has particular application to electric flat-irons although it obviously has other uses.

In carrying out my invention I provide a ratchet wheel for holding the circuit control means in closed circuit position and secure the ratchet wheel against rotation by means of a stem, one end of which extends through an off-center aperture in the ratchet wheel, the other end being secured by a fusible metal.

For a more complete understanding of my invention, reference should be had to the accompanying drawing in which Fig. 1 is an elevation view partially in section of an electric flat-iron embodying my invention; Fig. 2 is an enlarged plan view of the switching mechanism showing the switch in closed position; while Fig. 3 is an enlarged fragmentary view in section showing the anchoring means for the switch holding member.

Referring to the drawing, I have shown my invention in one form as applied to a well known type of flat-iron comprising a sole plate 10 and a pressure plate 11 between which is clamped a suitable electric resistance heating unit 12. As shown, the plates are secured together by means of a screw 13. In the sole plate is a circular recess 14 in which is secured a sealed receptacle 15 containing a suitable fusible metal or alloy 16. The receptacle 15 is made of suitable material such as steel and has its surface oxidized or otherwise treated or protected to prevent amalgamation at high temperature with the fusible metal, for example when the fusible metal is in a molten condition.

Extending upward from the receptacle 15, through a tapered circular opening 17 in the pressure plate, is a stem or switch holding member 18. This stem has a portion 19 of reduced size at its upper end, which portion extends through a suitable off-center aper-

ture in a horizontally disposed ratchet wheel 20 cooperating with the switching mechanism in the circuit of the heating unit 12. The lower end of the stem 18 extends into the receptacle 15 and is normally secured by the fusible metal. When so secured the stem secures the ratchet wheel against turning and thereby holds the switching mechanism in closed circuit position. Upon the occurrence of an excessive temperature resulting in fusing of the alloy metal, the stem is freed and can swing around to allow an appreciable rotation of the ratchet wheel whereby the switching mechanism is released and the heating circuit opened.

Any suitable switching mechanism may be used in the circuit of the heating unit 12. The particular switching mechanism shown is described and claimed in United States Patent No. 1,439,979 to Earl H. Richardson, dated December 26, 1922, and therefore will not be described in detail.

The ratchet wheel 20 is secured to the lower end of a shaft 21. This shaft is rotatably mounted in a vertical position on brackets 22 and 23 formed by striking upward and suitably shaping the end of a metallic supporting plate 24, which is secured on the top of the pressure plate 11. The shaft may be upheld by means of a washer 24 secured on its upper end resting on bracket 22, and prevented from sliding upwards by means of a shoulder on its lower end engaging the lower side of the bracket 23. An aperture 25 is provided in the bracket 23 through which the ratchet wheel projects toward the left hand, as viewed in Fig. 2. The ratchet is prevented from rotating in a clockwise direction, as viewed in Fig. 2, by means of a spring arm 26 secured at one end to the bracket 23 and having its free end in engagement with the teeth of the ratchet.

Rotation of the ratchet in a counter-clockwise direction is prevented normally by the stem 18 which is in turn secured by the fusible metal, and thus holds the switching mechanism in closed circuit position against the force exerted by a comparatively strong spiral spring 27. This spring has one end 28 adjustably secured to the supporting plate 24 while its other end is operatively connected through a link 29, yoke 30, and link 31

to the movable end of a switch arm 32. The other end of the switch arm is pivoted on a suitable knife edge bearings 33. The yoke member 30 is pivoted centrally on a loop 5 on one end of an operating arm 34, the other end of which is provided with knife edge bearings 35 on which the member 34 is pivoted. A right angle extension 34^a is provided on the member 34 and on this extension 10 is a spring latch 36 which cooperates with the teeth of the ratchet wheel 20 to secure the member 34 in closed circuit position against the force exerted by spring 27.

The action of the spring 27 is in such direction as to tend to throw the ratchet wheel in a counter-clockwise direction about its pivot and thus move the bridging circuit closing member 37 away from the stationary contacts 38 and 39 to open the heating circuit. As long as the ratchet wheel is secured by the fusible metal, as shown in Fig. 2, the switch is maintained closed by the engagement of the latch 36 therewith. In case of excessive temperatures, however, sufficient to fuse the metal 16, the stem 18 will be released allowing the ratchet wheel to rotate in a counter-clockwise direction, under the influence of the force applied by the spring 27, until latch 36 slips off the ratchet wheel whereupon the switch is opened by the spring 27. After the stem 18 has been again secured by the solidification of the fusible metal, the heating circuit may be closed by pressing inward on a button 40 which is pivotally attached to the operating member 34. The spring arm 26 prevents backing up of the ratchet wheel, due to any loosening of the parts, when the switch is being closed.

As shown in Fig. 3, the receptacle 15 for the fusible metal is provided with a cover 41 which is a flexible diaphragm made of a suitable metal, such as manganese nickel. The receptacle 15 has a flanged top upon which the cover or diaphragm 41 rests, a clamping ring 42 being placed on the diaphragm and the container sealed by means of a brazed or welded joint 43 between the flanged edge of the receptacle, the diaphragm and the clamping ring. The stem 18 is carried by the diaphragm 41 and extends centrally through it into the receptacle. A suitable anchor member 44 is preferably provided on the lower end of the stem. This anchor may consist of two prongs 45 and 46 which are embedded in the fusible metal 16 and thoroughly secure the stem. The stem is tightly secured to the diaphragm in this central position by means 50 of a brazed or welded joint 47. It will be observed that the receptacle 15 is thus sealed so that the fusible metal 16 is protected against oxidation. When the metal fuses, releasing the lower end of the stem, the diaphragm flexes so as to permit the stem to

swing about its point of support on the diaphragm and in effect provides a universal joint or pivot for the stem.

The axis of the shaft 21 passes through the point of support of stem 18 on the diaphragm and since the upper end of the stem passes through a hole in the ratchet wheel which is slightly offset from the center of the ratchet wheel, the stem therefore is tilted slightly. As the ratchet wheel is turned 70 each time to release the switch upon the occurrence of a predetermined temperature, it will be seen that the stem is swung to describe a portion of a cone, this movement being continued upon each release and the upper end of the stem describing a small circle.

For the purpose of preventing the fusible metal from coming in contact with the diaphragm 41, a disc 48 is secured to the stem 18 at its lower end just above the anchor member 44. Immediately above the disc 48 and in sliding engagement therewith is a washer 49 which fits snugly in the top of the receptacle 15 below the diaphragm. As the stem 18 swings about its pivot on the diaphragm the disc 48 slips freely with relation to the washer 49. The disc and the washer form a tight joint, however, and thus prevent the fusible metal from coming in contact with the diaphragm. The disc and washer are made of a suitable material for which the fusible metal has no affinity, such as mica.

While I have described my invention as embodied in concrete form and as operating in a specific manner in accordance with the provisions of the patent statutes, it should be understood that I do not limit my invention thereto, since various modifications 100 thereof will suggest themselves to those skilled in the art without departing from the spirit of my invention, the scope of which is set forth in the annexed claims.

What I claim as new and desire to secure 110 by Letters Patent of the United States, is:—

1. A temperature cut-out for electric heaters comprising control means in the circuit of said heater biased to open circuit position, a rotatable member for securing said control means in closed circuit position, a holding member for preventing rotation of said rotatable member having a pivotal off-center connection with said rotatable member, and temperature responsive means normally securing said holding member but releasing it to permit the opening of the heater circuit upon the occurrence of a predetermined temperature.

2. A temperature cut-out for electric heaters comprising control means in the circuit of said heater biased to one position, temperature responsive means, a pivoted member normally secured against pivotal movement by said temperature responsive means 120

but released upon the occurrence of a pre-determined temperature, a rotatable member, a connection between said rotatable member and said pivoted member whereby said rotatable member is normally secured against rotation by said pivoted member, and a latching connection between said control means and said rotatable member whereby said control means is normally held by said 10 rotatable member in another position.

3. A temperature cut-out for electric heaters comprising control means in the circuit of said heater biased to open circuit position, a rotatable member, a stem, a universal 15 pivotal support for said stem, an off-center pivotal connection between said stem and said rotatable member, and temperature responsive means normally securing said stem but releasing it to permit the opening of the 20 heater circuit upon the occurrence of a pre-determined temperature.

4. A temperature cut-out for electric heaters comprising control means in the circuit of said heater biased to open circuit position, 25 a rotatable member for securing said control means in closed circuit position, a stem, a pivotal off-center connection between said stem and said rotatable member, a flexible diaphragm forming a support for said stem 30 to which said stem is rigidly secured, said diaphragm flexing to permit pivotal movement of said stem in all directions, and a fusible metal for securing said stem whereby said rotatable member is normally held 35 against rotation but is released to permit the opening of the heater circuit upon the fusing of said metal.

5. A temperature cut-out for electric heaters comprising control means in the circuit 40 of said heater biased to open circuit position, a ratchet wheel for securing said control means in closed circuit position, a stem having an off-center pivotal connection at one end with said ratchet wheel, and a fusible 45 material for securing said stem whereby said ratchet wheel is normally held against rotation, but is released to permit the opening

of the heater circuit upon the fusing of said metal.

6. A temperature cut-out for electric heaters comprising control means in the circuit of said heater biased to open position, a receptacle, a flexible cover for said receptacle, a stem secured to said cover and extending into said receptacle, said stem being 55 pivotally movable by the flexing of said cover, a fusible metal in said receptacle normally securing said stem, a ratchet wheel for holding said switch in closed position, and an off-center pivotal connection between said 60 stem and said ratchet wheel whereby said ratchet wheel is normally secured against rotation by said stem, but released to effect the opening of said circuit upon the fusing of said metal. 65

7. A temperature cut-out for electric heaters comprising control means in the circuit of said heater biased to open circuit position, a receptacle, a flexible cover for said receptacle, a stem secured to said cover and extending into said receptacle, said stem having universal pivotal movement by the flexing of said cover, a fusible metal in said receptacle normally securing said stem, and a connection between said stem and said control 75 means whereby said control means is normally held in closed circuit position.

8. A temperature cut-out for electric heaters comprising control means in the circuit of said heater biased to open circuit position, 80 a stem having universal pivotal movement, temperature responsive means for securing said stem against pivotal movement, and a connection between said stem and said control means whereby said control means is 85 normally held in closed circuit position but released by said temperature responsive means upon the occurrence of a predetermined temperature.

In witness whereof, I have hereunto set 90 my hand this sixteenth day of December, 1924.

WILLIS N. VANATTA.
